US00D782143S

(12) **United States Design Patent** (10) **Patent No.:** **US D782,143 S**
(45) **Date of Patent:** **** Mar. 21, 2017**

(54) **WASTE RECEPTACLE**

(71) Applicant: **Vladislav Divizinskiy**, Lincoln, NE (US)

(72) Inventor: **Vladislav Divizinskiy**, Lincoln, NE (US)

(**) Term: **15 Years**

(21) Appl. No.: **29/541,475**

(22) Filed: **Oct. 5, 2015**

(51) LOC (10) Cl. **09-09**

(52) U.S. Cl.

USPC **D34/1**

(58) **Field of Classification Search**

USPC ..... D34/1-11; 220/908, 910, 200, 911, 220/495.01, 495.04, 495.05, 913, 220/700-702, DIG. 13, 23.4, 476, 482, 220/694-697, 359.1; D32/53, 53.1, 54; D7/637, 509, 553.1, 554.2, 603-608; D19/81, 77, 65, 78, 99, 75, 90, 91, 85; D18/34.9; 206/214, 224, 371, 315.11, 206/541, 505, 503, 507, 518; 47/67; 215/237, 6; 4/258, 263; D9/756, 749, D9/755, 760; D3/304-315, 206, 266; D6/756, 694, 698, 710, 744, 745, 749, D6/755, 760, 574, 573, 512-514, 668, D6/672, 673, 682.1, 553; D14/215; 379/440, 435, 455; 211/10, 11, 50, 13.1, 211/42, 45, 46; 248/220.21

(57) **CLAIM**

The ornamental design for a waste receptacle, as shown and described.

DESCRIPTION

FIG. 1 is a perspective front to top side view of a waste receptacle showing my new design;

FIG. 2 is a front view thereof;

FIG. 3 is a back view thereof;

FIG. 4 is a right side view wherein a left side view is a mirror image of thereof;

FIG. 5 is a top plan view; and,

FIG. 6 is a bottom plan view thereof.

1 Claim, 6 Drawing Sheets
